[57] CLAIM

The ornamental design for a gun-shaped computer, as shown and described.

DESCRIPTION

FIG. 1 is a right side perspective view of a gun-shaped computer in accordance with the present design with a gun barrel and trigger guard connected to a gun handle to form the gun shape;

FIG. 2 is a left side perspective view thereof;

FIG. 3 is a right side elevational view thereof;

FIG. 4 is a left side elevational view thereof;

FIG. 5 is a front end elevational view thereof;

FIG. 6 is a rear end elevational view thereof;

FIG. 7 is a top plan view thereof;

FIG. 8 is a bottom plan view thereof;

FIG. 9 is a right side perspective view of the gun handle shown separately for clarity of illustration only;

FIG. 10 is a left side perspective view of the gun handle;

FIG. 11 is a left side perspective view of the gun barrel and trigger guard shown separately for clarity of illustration only;

FIG. 12 is a right side perspective view of the gun barrel and trigger guard;

FIG. 13 is a right side perspective view of the gun barrel and trigger guard connected to the gun handle without forming the gun shape; and,

FIG. 14 is a left side perspective view of the gun barrel and trigger guard connected to the gun handle without forming the gun shape.
